DESIGN FOR A SUIT BUTTON

Peary Cohen, Waterbury, Conn., assignor to The Waterbury Button Company, Waterbury, Conn., a corporation of Connecticut

Application March 7, 1941, Serial No. 99,406

Term of patent 7 years

To all whom it may concern:

Be it known that I, Peary Cohen, a citizen of the United States, residing in Waterbury, county of New Haven and State of Connecticut, have invented a new, original, and ornamental Design for Suit Buttons, of which the following is a specification, reference being had to the accompanying drawing, forming part thereof.

Fig. 1 is a front face view of the suit button, showing my new design.

Fig. 2 is a side view of the same.

I claim:

The ornamental design for a suit button, as shown.

PEARY COHEN.
